(57) **CLAIM**

The ornamental design for a baffle vent with transverse ribs for use in roof ventilation, as shown and described.

DESCRIPTION

FIG. 1 is a top plan view of a first embodiment of a baffle vent with transverse ribs for use in roof ventilation showing my new design, this first embodiment being constructed for deployment between two adjacent roof rafters in a building structure;

FIG. 2 is an end elevational view thereof;

FIG. 3 is a side elevational view thereof;

FIG. 4 is a perspective view thereof;

FIG. 5 is an enlarged partial side elevational view of my new design to show the transversely extending ribs;

FIG. 6 is a top plan view of a baffle vent with transverse ribs for use in roof ventilation showing my new design in an embodiment that is constructed for deployment to span several roof rafters;

FIG. 7 is an end elevational plan view of the embodiment of the baffle vent with transverse ribs for use in roof ventilation depicted in FIG. 6;

FIG. 8 is a top plan view of my baffle vent with transverse ribs for use in roof ventilation design forming the body portion of a baffle vent with transverse ribs for use in roof ventilation incorporating an integral drift blocker which is shown in phantom and does not form a part of my baffle vent with transverse ribs for use in roof ventilation design;

FIG. 9 is an end elevational view of the baffle vent with transverse ribs for use in roof ventilation shown in FIG. 8;

FIG. 10 is an alternative embodiment of my baffle vent with transverse ribs for use in roof ventilation design incorporating a return lip along the transverse edges thereof and forming the body portion of a baffle vent with transverse ribs for use in roof ventilation incorporating an integral drift blocker which is shown in phantom;

FIG. 11 is an end elevational view of the baffle vent with transverse ribs for use in roof ventilation shown in FIG. 10; and,

FIG. 12 is a perspective view of the baffle vent with transverse ribs for use in roof ventilation shown in FIG. 8 with the integral drift blocker being shown in phantom.
